CLAIM

The ornamental design for a telephone set, as shown and described.

DESCRIPTION

FIG. 1 is a perspective view from the left side and above of the top of a telephone set showing my new design;

FIG. 2 is similar perspective view thereof with the handset removed for clarity of illustration;

FIG. 3 is also a similar perspective view of a second embodiment thereof with the handset omitted for clarity of illustration;

FIG. 4 is a rear elevational view of the embodiments thereof as shown in FIGS. 2 and 3; and

FIG. 5 is an elevational view of the side of the embodiments of the set opposite to that shown in FIG. 1.

The numerals and symbols shown in the various figures of the drawing are exemplary only, and are not part of the present design.

The broken line showing of numerals and symbols shown in various figures of the drawings is for illustrative purposes only and forms no part of the claimed design.
